(57) **CLAIM**

The ornamental design for a bag clip, as shown and described.

DESCRIPTION

FIG. 1 is a front perspective view of a bag clip showing my new design;

FIG. 2 is a rear perspective view thereof;

FIG. 3 is a front elevation view thereof;

FIG. 4 is a rear elevation view thereof;

FIG. 5 is a right side elevation view thereof, the left side elevation view being a mirror image thereof;

FIG. 6 is a top plan view thereof; and,

FIG. 7 is a bottom plan view thereof.

The broken line showing of a bag in FIGS. 1 and 2 illustrates environment only and forms no part of the claimed design.
